Primary Examiner—Paula A. Mortimer

[57] **CLAIM**

The ornamental design for a neckwear, as shown and described.

DESCRIPTION

FIG. 1 is a front elevational view of neckwear showing my new design;

FIG. 2 is a back elevational view of the neckwear of FIG. 1; FIG. 3 is a left side elevational view of the neckwear of FIG. 1;

FIG. 4 is a right side elevational view of the neckwear of FIG. 1;

FIG. 5 is a top plan view of the neckwear of FIG. 1;

FIG. 6 is a bottom plan view of the neckwear of FIG. 1; and, FIG. 7 is a top, front, right side perspective view of the neckwear of FIG. 1 in use.

The broken lines showing of a shirt collar in FIG. 7 are for illustrative purposes only and form no part of the claimed design.
